Primary Examiner — John Windmuller*Assistant Examiner* — Luqman McNeil(74) *Attorney, Agent, or Firm* — Sheridan Ross P.C.(57) **CLAIM**

The ornamental design for a remote control, as shown and described.

DESCRIPTION

FIG. 1 is a perspective view of the remote control showing the new design;

FIG. 2 is a front elevation view thereof;

FIG. 3 is a right elevation view thereof, the left elevation view being a mirror image thereof; and

FIG. 4 is a top plan view thereof; and,

FIG. 5 is a bottom plan view thereof.

The broken lines depict environment and comprise no part of the claimed design.

1 Claim, 3 Drawing Sheets(56)
